No. 831,360.

PATENTED SEPT. 18, 1906.

F. J. LEIGHT.
GARMENT STRETCHER.
APPLICATION FILED JAN. 29, 1906.

UNITED STATES PATENT OFFICE.

FREDERICK J. LEIGHT, OF DAYTON, OHIO, ASSIGNOR TO J. R. FASSIG,
OF COLUMBUS, OHIO.

GARMENT-STRETCHER.

No. 831,360.

Specification of Letters Patent.

Patented Sept. 18, 1906.

Application filed January 29, 1906. Serial No. 298,409.

To all whom it may concern:

Be it known that I, FREDERICK J. LEIGHT, a citizen of the United States, residing at Dayton, in the county of Montgomery and 5 State of Ohio, have invented certain new and useful Improvements in Garment-Stretchers, of which the following is a specification.

My invention relates to new and useful improvements in garment-stretchers, and more 10 particularly to a device for stretching and creasing trousers.

The object of the invention is to provide a stretcher which will efficiently crease and stretch trousers in a comparatively short 15 time without distorting the shape or otherwise injuring the same.

Another feature resides in the provision 20 of a flexible or resilient board, which is adapted to be bent or folded so that its free ends come together, thus providing a smooth and continuous body over which the trousers are stretched. Also by provision of this board 25 one or more damp cloths may be used to more effectually carry out the stretching and creasing operation.

Finally, the object of the invention is to provide a stretching device which will be strong and durable, simple and comparatively inexpensive to manufacture, and one 30 in which the several parts will not be liable to get out of working order.

With the above and other objects in view 35 the invention consists of the novel details of construction and operation, a preferable embodiment of which is described in the specification and illustrated in the accompanying drawings, wherein—

Figure 1 is a plan view of the stretcher in its flat or open position. Fig. 2 is a side or 40 rear elevation of the stretcher bent or folded, with its ends secured together and a pair of trousers arranged thereon in the stretching position; and Fig. 3 is a transverse sectional view taken on the line xx of Fig. 1.

In the drawings the numeral 1 designates 45 a flexible or resilient board, which tapers from one end to the other, thus producing a broad end and a narrow end, so as to have somewhat the general shape of the leg of a pair of trousers. This board may be formed 50 in various ways and of different materials. However, I have found it more practical and expedient to construct the board of a number of transversely-arranged slats 2. These

slats exhibit in cross-section a substantially 55 triangular shape, with the apex of the triangle cut off, as best shown in Fig. 2. The slats thus shaped are placed so that their broadest or flat portions 3 lie flush and provide a substantially smooth and continuous surface, 60 each slat being separated from the other by a triangular or tapered space. At each end of the board and in engagement with the end slats binding-strips 4 are arranged. Suitably-spaced wires 15 are passed through the 65 strips and slats transversely of the same and longitudinally of the board and at each end bent over and embedded in the outer sides or edges of the strips 4 at 16^a. In this way the slats and strips are securely held together 70 and a flexible or resilient board provided.

Through the ends of the binding-strips 4 suitable bolts 5 are passed, so as to project some distance thereabove. These bolts pass 75 through slots 7, provided in the ends of clamps or bars 8 and are threaded to receive wing-nuts 9. In the upper face of each clamp 8 a metal plate 10 is embedded and cut out around the slots, as indicated in Figs. 1 and 3. The slots 7 are longer than the 80 slots 6, and the metal plates 10 are turned down, so as to close one end of each of the slots 7, as indicated at 11. Each slot 7 has such a length as to permit the clamp to be moved longitudinally or transversely of the 85 board to withdraw the slot 6 from about its bolt 5. The clamps thus arranged are free to swing to one side and allow the trousers to be readily placed on the board. While the clamps are free to swing, they are at the 90 same time still connected to the board by the closures at the ends of the slots 7.

In carrying out the stretching operation the board is placed as shown in Fig. 1—that is, disposed flat—and the broadest portions 3 95 of the slats 2 uppermost. The wing-nuts 9 having been loosened and the clamps 8 swung to one side, a suitable cloth 12, (see Fig. 2,) first dampened, is laid on the board. The trousers properly folded so as to crease 100 in the desired places are laid on this cloth, the same being indicated by the numeral 13 in Fig. 2. A second cloth 14, suitably dampened, is then placed on top of the trousers. It is to be understood that both cloths may 105 be used or either one used alone, if desired. However, the best results are produced by using the two cloths. The clamps 8 are now

swung into position and moved so that their slots 6 receive the bolts 5. The wing-nuts 9 not having been removed are screwed down onto the plates 10, thus firmly securing the 5 clamps in place. By thus securing the clamps the trousers and cloths are firmly fastened between the same and the strips 4. It is of course necessary to have the cloths and trousers as smooth as possible and to 10 stretch them as tight as possible by hand between the clamps. The parts now having been made ready the board 1 is inverted and bent or folded so as to bring the free ends toward each other and the strips 4 together, 15 as shown in Fig. 2. The tapered spaces between the slats 2 permit the board to readily bend and the wires 15 prevent sharp angles or rough places resulting from the bending. This bending of the board elongates the 20 same to such an extent as to draw the cloths and the legs of the trousers tightly over its outer surface. An eye 5^a, carried by one of the strips 4, is engaged by a hook 16, carried by the other strip, so that the board is held 25 in its bent position. Any suitable means may be provided for suspending the stretcher during the stretching operation. The parts remain in this position until the stretching is completed, when the hook is disengaged 30 from the eye 5^a and the board inverted and flattened out to the position shown in Fig. 1, the nuts 9 then loosened, the clamps swung to one side, and the trousers and cloths removed. Trousers thus stretched and

creased will retain their shape for some time 35 until stretching and creasing are again necessary.

What I claim is—

1. In a device for stretching trousers, a board comprising a plurality of transverse 40 slats, wires for flexibly connecting the slats, binding-strips arranged at each end of the board engaged by the wires, and clamping devices engaging with the strips for holding a pair of trousers on the board. 45

2. In a device for stretching trousers, a flexible body composed of a plurality of transversely-disposed slats, flexible members extending the entire length of said body and which bind all of said slats together, and 50 clamping members for clamping a garment upon said stretching device.

3. A device for stretching trousers comprising a plurality of transversely-disposed slats, the outer faces of which are wider than 55 the inner faces thereof, flexible means for binding all of said slats together, means for securing a garment upon said stretching device, and means for securing the ends of said stretching device directly to each other when 60 said device is bent to bring said ends together.

In testimony whereof I affix my signature in presence of two witnesses.

FREDERICK J. LEIGHT.
